(57) **CLAIM**

The ornamental design for bath organizer as shown and described.

DESCRIPTION

FIG. 1 is a front perspective view of a bath organizer, showing my new design.

FIG. 2 is a top plan view thereof.

FIG. 3 is a front elevation view thereof.

FIG. 4 is a right-side elevation view thereof.

FIG. 5 is a rear elevation view thereof.

FIG. 6 is a bottom plan view thereof.

FIG. 7 is a left-side elevation view thereof; and,

FIG. 8 is a front perspective view thereof showing a removable insert to a rear chamber removed for ease of illustration. The broken lines shown in the drawings show portions of the bath organizer which form no part of the claimed design.

1 Claim, 8 Drawing Sheets
